UNITED STATES PATENT OFFICE.

CARL C. CAMERON, OF SLATER, MISSOURI; MAE A. CAMERON EXECUTRIX OF SAID
CARL C. CAMERON, DECEASED.

GATE CONSTRUCTION.

1,413,157.

Specification of Letters Patent. Patented Apr. 18, 1922.

Application filed April 7, 1919. Serial No. 288,380.

To all whom it may concern:

Be it known that I, CARL C. CAMERON, a citizen of the United States, residing at Slater, in the county of Saline, State of Missouri, have invented certain new and useful Improvements in Gate Constructions, of which the following is a complete specification.

The present invention relates to gate structures, and one of the objects in view is to provide a novel form of gate supporting means whereby the gate frame is allowed not only a pivotal swinging movement about its fixed supporting axis but also a swinging movement about an axis intermediate the sides of the gate frame.

To this end I have devised a hanger supporting member which is mounted upon a fixed supporting axis and also pivotally connected with the gate frame for suspending the latter for pivotal swinging movement about a vertical secondary axis which shifts in accordance with the position of the gate frame.

25 A further object is to provide a gate structure having a hanger supporting member of the character described and also including provision for limiting the swinging movement of the gate about its secondary or shifting axis in one of the directions of said movement.

Incidentally it is sought to devise a novel gate construction with particular reference to stock chutes for the loading or unloading 35 of cars with a view to providing a safe, convenient and efficient gate arrangement for closing the sides of the passageway across the platform from the chute to the car.

With these general objects in view the invention will now be described with reference to the accompanying drawing illustrating a practical form of construction which has been devised for embodying the proposed improvements, after which the novel features therein will be set forth and defined in the appended claims.

In the drawing—

Figure 1 is a plan view of a stock chute platform and showing one end of the chute and a portion of the car, with the passage across the platform closed in by gates constructed in accordance with the present invention;

Figure 2 is an enlarged detail plan view 55 of one of the gates and the associated parts

occupying the same position as in Figure 1, with broken lines illustrating another position of the gate;

Figure 3 is a section taken on the line 60 3—3 of Figure 1;

Figure 4 is a perspective view of one of the gates; and

Figures 5 and 6 are side and edge views, 65 respectively, of a modified form of the gate construction.

Referring to the drawing in detail, this shows in Figure 1 the floor 8 of a stock chute leading to a platform 10, across which stock is passed in being unloaded from or loaded into a car 12. The chute has the 70 side walls 14, and to the posts 16 at the edge of the platform 10 are secured pintles 18 for the pivotal mounting of gate hangers 20 for swinging movement about vertical fixed axes at the opposite sides of the chute. 75 Each hanger 20 is of general U-shape, having the terminal eyes 22 for fitting over the pintles 18, and the vertical or intermediate portion of the hanger is pivotally connected to the top and bottom cross pieces 24 of one 80 of the gate frames by means of brackets 26. These brackets 26 are located intermediate the sides of the gate frame, whereby the latter swings in the hanger about a vertical movable axis which shifts in accordance with 85 the changing position of the gate with reference to the axis of the hanger.

In the construction shown in Figures 1 to 4, the hanger is also provided with a vertical rod or connection 28 joining the upper 90 and lower arms of the hanger; this vertical rod is in position to form a stop for engagement with the gate frame (as by engagement with one of its vertical side pieces 30) for the purpose of limiting the swinging 95 movement of the gate and preventing that side of the gate from passing on through the space between the fixed and movable gate axes above described. It will also be noted that the horizontal leg portions of the 100 hanger are of bent or angular form and of a length permitting the gate to swing to such an extent as to bring one side thereof into a position intersecting a plane passing through said fixed and movable axes, 105 as shown in Figure 2. A modification of this stop means is illustrated in Figures 5 and 6, in which the vertical rod or connection between the arms of the hanger is omitted, and the side members 30 of the 110

gate are extended to form projections 30' adapted to engage the arms of the hanger and thus limit the movement of the gate frame in the same manner as above described. In either case the stop means serves to stop the swinging movement of the frame when the engaged side thereof comes into position intersecting a plane passing through the fixed and movable axes of the frame, with the plane of the latter at a slight angle with reference to the plane of said axes.

In the illustrated application or mode of use of the gate structure, the gate frame is of such width as to extend across the platform 10 and project within the doorway of the car with the outer side members 30 of the gate frame resting against the jambs 32 at each side of said doorway.

A simple and practical form of gate structure is thus provided for carrying out the desired objects of the invention, and the improved construction has special advantages in the particular relation illustrated in the drawing. It is common practice to employ swinging gate frames for stock chute platforms, but to construct these gate frames of such width as not to project entirely across the platform and to prop or brace the gates in the desired position. The purpose of using these narrower gates is to clear the sides of the cars in order to avoid damage being done to the cars or the gates in the event of casual movement of the cars. But such damage is not altogether avoided by the use of the narrower gate frames because of the fact that the common type of gate employed is mounted to swing about a single axis, and when an object collides with it directly in line with its axis the gate is not permitted to swing. Consequently, when gates of this single pivoted type are unfastened and free to swing (as they commonly are, especially when not in use for loading or unloading) they frequently assume such positions with reference to the sides of the car as to be caught by objects projecting out from the car, and often cause serious personal injuries to trainmen aboard the sides of the car in the path of the gates. The present improved gate avoids any possibility of such damage or injury taking place, for the double pivoted movement allows the gate to swing freely in either direction, and in the case of a thrust edgewise against the gate it simply moves backward entirely out of the path of the object colliding with it. Therefore, the gates may safely be projected entirely across the platform and into the doorway of the car, and thus form continuous and complete closures for the passageway across the platform, and in this position they require no braces or props for securing them against spreading outward toward

the ends of the platform. When the gates are not in use they are simply pushed backward into the end of the chute, as represented by the broken lines in Figure 2. Preferably, the upper pintles 18 are located 70 slightly out of line with the lower pintles in such a way as to cause the gates to tend to swing toward and rest against the jambs 32 or the walls 14, as the case may be.

While I have illustrated and described 75 what have been found to constitute simple and practical forms of embodiment of the improvements, I desire to reserve the right to make such formal changes or modifications as may fairly fall within the scope 80 of the appended claims.

What I claim is:

1. A gate construction comprising a gate frame, a pivoted hanger provided with horizontal arms hingedly connected with 85 one of the faces of said frame for supporting the same for swinging movement about a vertical movable axis intermediate the ends of the frame and shifting with the position thereof, and also for swinging 90 movement about an approximately vertical fixed axis, the arms of said hanger being of a length sufficient to permit swinging movement of said frame into a position that one end thereof intersects the plane of the 95 fixed and movable axes intermediate said axes, and stop means operative to limit said swinging movement and stop the frame at a slight angle to said plane with one end thereof in a position intersecting a plane 100 passing through said fixed and movable axes and with the plane of the frame at a slight angle with reference to the plane of said axes.

2. A gate construction for stock chutes, 105 comprising a gate frame, and a pivoted hanger supporting said frame for swinging movement about an approximately vertical fixed axis, said hanger having horizontal bent arms connected by spaced vertical 110 rod portions, one of said vertical rod portions being connected with one of the faces of said frame for supporting the latter for swinging movement about a vertical axis intermediate the ends of said frame and 115 shifting with the positions thereof, the other of said vertical rod portions of the hanger joining the bent portions of said arms and being adapted to engage the other face of said frame and limit the swinging 120 movement thereof about said first vertical rod portion of the hanger, the length of said arms being sufficient to permit swinging movement of said frame into position bringing one end thereof into a line intersecting 125 a plane passing through said fixed and movable axes.

In witness whereof I affix my signature.

CARL C. CAMERON.
